UNITED STATES PATENT OFFICE

100,930

DESIGN FOR A BOTTLE

William R. Thomas, Los Angeles, Calif., assignor
to The California-Florida Company, Los Angeles, Calif., a corporation of California

Application April 11, 1935, Serial No. 56,327

Term of patent 14 years

To all whom it may concern:

Be it known that I, William R. Thomas, a citizen of the United States, residing at Los Angeles, in the county of Los Angeles, and State of California, have invented a new, original, and ornamental Design for a Bottle, of which the following is a specification, reference being had to the accompanying drawing forming a part thereof.

In the drawing, Fig. 1 is a top plan view of a bottle showing my new design, and Fig. 2 a front view of the same.

My bottle design is characterized by a bulged smooth surfaced lip, a straight stippled wall uniformly gradually flaring from the lip to a point

well below the longitudinal center of the bottle to define an elongated frusto-conical section, the straight wall then merging into a reversely curved stippled wall which defines a relatively wide reduced section and a bulged section constituting the major diameter of the bottle, and a narrow smooth surfaced tapering base section. The bottle carries near the base of its frusto-conical section a colored disk above which the bottle wall has a smooth surfaced curved area.

I claim:

The ornamental design for a bottle, as shown and described.

WILLIAM R. THOMAS.
